RECUPERATOR SYSTEM FOR AIRPLANE
CANNONS

Harold N. Metzel, East Lansing, Mich., assignor to
General Motors Corporation, Detroit, Mich., a
corporation of Delaware

Application September 14, 1945, Serial No. 616,329

2 Claims. (Cl. 89—43)

1

This invention relates to a recuperator for airplane cannon.

In mounting a cannon in an airplane, it is not always possible to place the cannon with the trunnions in a horizontal position. Sometimes the cannon must be tilted or turned slightly on its axis to make it fit or seat properly in the gun mount.

The recuperator system usually provided on the 37 mm. Automatic Gun M 9 or like cannon generally has an expansion chamber, which because of the location of the recuperator cylinder immediately below the barrel, is offset with respect to the vertical axis of the gun, with the result that when the gun is tilt mounted, the chamber may come on the low side. In this case, when filling or replenishing the oil supply in the recuperator system, the expansion chamber might become filled with oil instead of air or conversely, some air might get into the cylinder displacing oil that should be in it.

In order to guard against this contingency, it is the purpose of this invention to provide means for assuring that when the recuperator system is filled or replenished, air does not get into the cylinder and that a substantially uniform volume air pocket is retained in the expansion chamber.

Accordingly it is the object of this invention to provide, in connection with a recuperator system, alternate means for assembly of a detachable expansion chamber, whereby such chamber may be attached in a position that will assure entrapment of air within the expansion chamber and preclude any air being retained in the recoil cylinder.

The specific nature of the invention as well as other objects and advantages thereof will clearly appear from a description of a preferred embodiment as shown in the accompanying drawings in which:

Fig. 1 is a schematic view of a generalized application of this invention to any hydraulic cylinder;

Fig. 2 is a plan view of a particular application of this invention, namely, the recuperator cylinder of an automatic cannon;

Fig. 3 is a perspective view of one end of the recuperator of Fig. 2 shown with the end cap removed;

Fig. 4 is a sectional view of Fig. 2 taken along the plane 4—4 thereof;

Fig. 5 is a sectional view of Fig. 2 taken along the plane 5—5 thereof;

Fig. 6 is a view similar to Fig. 4 but showing the recuperator in a tilted position; and

2

Fig. 7 is a view similar to Fig. 5 but showing the recuperator in the same tilted position as Fig. 6.

The invention as illustrated schematically in Fig. 1 comprises an hydraulic cylinder 31, a plurality of sockets 33 connected to cylinder 31 by passages 34, and an expansion chamber 32 constructed to be selectively assembled in any socket 33. An orifice 35 for filling hydraulic cylinder 31 is provided adjacent each socket 33 and a bleeder passage 36 is provided in each socket 33 for bleeding, together with means for sealing the orifice and passage 35 and 36 respectively. Spare plugs 39 are provided for sealing the unused sockets 33.

The schematic structure above described is arranged so that there will be a socket 33 for assembly of the expansion chamber 32 above the level of the cylinder, a connecting passage 34 leading thereto from the upper portion of the cylinder, and a bleeder passage 36 leading through socket 33 into the lower part of the chamber when the cylinder 31 is rotated to any position up to sixty degrees each side of the vertical.

A specific application of this invention is illustrated in Figs. 2 through 7 in which an hydraulic cylinder 1, of the type utilized in automatic cannon is provided with diametrically opposed integral lugs 3 at the forward end of cylinder 1, each lug being provided with two bolt holes 4 (Fig. 3). In Figs. 4 and 5 the cylinder 1 is shown in the horizontal position and in Figs. 6 and 7 in an angular position with a gun barrel 2, in phantom. A top yoke 5 is assembled on cylinder 1, adjacent lugs 3 and is provided with bolt holes 6 matching holes 4 in lugs 3. A bottom yoke 7 with matching bolt holes 8 is provided and both yokes are secured in assembly 40 to cylinder 1 by means of bolts 9. Screws 10 are provided for added security in holding yoke 5 in exact location tightly against cylinder 1.

Two integral protuberances 12 extend upwardly and outwardly from each side of yoke 5 in a plane perpendicular to the axis of cylinder 1. Each protuberance 12 and the wall of cylinder 1 adjacent thereto is provided with an aperture or passage 13 extending from the inside of cylinder 1 up and out through the top of protuberance 12. A removable plug 14 is provided for sealing the passage 13. This passage serves as a filler hole for introducing hydraulic fluid into the recoil system.

Each protuberance 12 terminates in a receptacle or socket 17 opening rearwardly and some-

what upwardly and is provided with an inside threaded recess 18. An expansion chamber 19, preferably comprising a hollow cylinder, is provided for selective threadable assembly in either socket as desired and a plug 20 is provided for sealing the other socket.

Each protuberance 12 is provided with three apertures or passages, the first being the filler passage 13 described above. The second passage 21 extends from the bottom inside of socket 17 to the upper part of cylinder 1 as shown in Fig. 2. The third passage 22 extends horizontally forward from a point near the top inside of socket 17. A plug 23 is provided to seal each passage 22, which passage will hereafter be referred to as the bleeder, its purpose being to drain off the excess of hydraulic fluid when the system is filled.

An airplane cannon is of course preferably installed with the trunnions horizontal, but this is not always possible. If the mounting is horizontal, expansion chamber 19 can be assembled in either socket, but if it is tilted toward one side then the chamber is assembled in the socket on the high side and plug 20 is used to seal the other socket. Plugs 14 and 23 in the same side as the air chamber are then removed and buffer oil is introduced through passage 13, filling cylinder 1 and then rising through passage 21 into expansion chamber 19 until it reaches the level of bleeder 22. Any excess of fluid beyond the amount required to raise the level thereof to bleeder 22 will drain out through the bleeder, after which plugs 14 and 23 are again secured tightly in place thereby sealing filler hole 13 and bleeder 22.

The air necessary for proper functioning of the recoil system is therefore trapped in expansion chamber 19, since it is largely above the level of bleeder 22 and the hydraulic fluid cannot run up into it to displace air therefrom above the level of bleeder 22, whereas had the chamber been installed on the lower side and the corresponding passages used for filling and bleeding, much or possibly even most of the chamber would have been filled with oil displacing the air therefrom since a larger proportion of the volume of the chamber would have been below the level of bleeder 22, and furthermore air would very likely have worked up into cylinder 1.

In the position shown in Figs. 6 and 7, the position of the recuperator elements is shown for the approximate maximum tilting of the cannon. At this angle, expansion chamber 19 has approached so near the horizontal that fluid up to the level of bleeder 22 is beginning to extend out into the chamber 19 and fill an increased proportion thereof. Any further tilting will result in an increase in the amount of fluid that will be retained in chamber 19 with a corresponding decrease in the amount of air entrapped thereby reducing the compressible properties.

When the fluid has reached its proper level in chamber 19 it will be noted that the socket 17 having plug 20 assembled therein, has a minute amount of air entrapped therein as shown in Figs. 5 and 7, but has no detrimental affect upon the functioning of the device.

Thus it is evident that the specific structure shown in the drawings is designed to permit tilting to approximately 60° each side of the normal vertical axis. If a greater tilting than 60° is likely to be encountered, then the angular displacement of the chamber 19 and bleeder 22 would have to be somewhat increased. Accord-

ingly, it will be evident to those skilled in the art that although the layout shown is designed to meet the requirements of tilting up to a maximum of 60° each side of the vertical, this limit can be easily increased by increasing the angular displacement or by provision of additional sockets.

With the firing of the cannon, heat is developed in the cylinder as a result of the work done in absorbing the energy of recoil by the reciprocation therein of a piston (not shown). This results in expansion of the oil with a consequent reduction in volume of the air pocket. However, due to compressibility of the air trapped in expansion chamber 19, the pressure developed is comparatively slight with the result that the danger of forcing any of the buffer oil past the packings (not shown) is generally negligible. Any loss of oil under such conditions would result in a partial vacuum when the gun cooled and might lead to air then being drawn into the cylinder. In case this occurred the presence of any appreciable volume of air within the cylinder would tend to reduce the resistance to motion of the piston, because of the lack of viscosity of air with the result that the hydraulic damping of the recoil stroke would be reduced and with increased volume of air within the cylinder would be virtually destroyed.

Although described in connection with an airplane cannon, it is to be distinctly understood that this specific application is illustrative only and in no way limits the scope of application of the invention.

It is therefore apparent that this invention provides a means for assuring that air will be trapped in the expansion chamber and not in the recoil cylinder, during filling or replenishing of the recuperator system.

I claim:

1. In a cannon recuperator having a hydraulic cylinder the improvement comprising, a top and bottom yoke mounted on the forward end of the cylinder, said top yoke having a pair of angularly disposed boss-like members in a plane perpendicular to the axis of the cylinder, each of said bosses being provided with a threaded recess opening rearwardly and inclined upwardly and a passageway therefrom communicating with the interior of the hydraulic cylinder, vent means near the upper end of each of said bosses communicating with said recess, an expansion chamber adapted to be threaded into said recess of one of said bosses, said passageway permitting hydraulic fluid to enter said chamber, and a plug threaded into said recess of said other boss for sealing said passageway, said vent means being provided for bleeding said chamber whereby a limited amount of air may be trapped therein when the cylinder and part of said chamber are filled with hydraulic fluid.

2. In combination with a cannon recuperator having a hydraulic cylinder, a top and bottom yoke adapted to surround the cylinder, said top yoke having a plurality of sockets extending therefrom in a plane perpendicular to the axis of the cylinder, each of said sockets being provided with a threaded recess terminating in an opening therefrom to permit the passage of hydraulic fluid from the cylinder and vent means near the upper end of said socket communicating with said recess, an expansion chamber adapted to be selectively secured in said recess of any one of said sockets whereby said chamber is maintained in an elevated position above the cyl-

indef, said chamber being thereby arranged to trap a pocket of air therein when hydraulic fluid enters said chamber, and a removable plug screwed into each of the remaining sockets to prevent escape of hydraulic fluid, said vent means being provided for bleeding said chamber whereby a uniform volume of air is provided therein.

HAROLD N. METZEL.
